US0D1081607S

(12) **United States Design Patent** (10) **Patent No.:** **US D1,081,607 S**
(45) **Date of Patent:** **** Jul. 1, 2025**

(54) **CIRCUIT BOARD**

(71) Applicant: **Chuanxin Chen**, Meizhou (CN)

(72) Inventor: **Chuanxin Chen**, Meizhou (CN)

(**) Term: **15 Years**

(21) Appl. No.: **29/986,440**

(22) Filed: **Jan. 17, 2025**

(51) LOC (15) Cl. **13-03**

(52) U.S. Cl.

USPC **D13/182**

(58) **Field of Classification Search**

USPC D13/182, 147, 133, 162, 199; D14/433, D14/435, 435.1

CLAIM

The ornamental design for a circuit board, as shown and described.

DESCRIPTION

FIG. 1 is a front perspective view of a circuit board, showing my new design;

FIG. 2 is a rear perspective view thereof;

FIG. 3 is a bottom view perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view.

The broken lines in the drawings illustrate the portions of the circuit board, which form no part of the claimed design.

1 Claim, 9 Drawing Sheets
